UNITED STATES PATENT OFFICE.

JOHN E. MITCHELL, WILLIAM WOLFE, AND DENNIS PARKS, OF ST. LOUIS, MISSOURI.

HEEL-BUILDING MACHINE.

1,352,302.

Specification of Letters Patent. Patented Sept. 7, 1920.

Application filed September 14, 1918. Serial No. 254,137.

To all whom it may concern:

Be it known that we, JOHN E. MITCHELL, WILLIAM WOLFE, and DENNIS PARKS, citizens of the United States, residing in the city of St. Louis and State of Missouri, have invented new and useful Improvements in Heel-Building Machines, of which the following is a specification:

The general object of the invention is to provide a heel building machine in the use of which the lifts are pasted and assembled by hand, and then, by the action of the machine, formed, nailed and compressed, and held under compression until the paste has set and the completed heel blank automatically discharged from the machine.

The invention is designed more particularly for use in building decked heels, and one of the salient features thereof is the provision of novel means for automatically alining the lifts and forming them into the desired configuration of the heel blank before the compressing and nailing operation.

Another important feature of the invention is the provision of means for enabling the operator to readily assemble the lifts in the clear, and outside the path of the downwardly-moving parts which act to compress and nail together the compiled lifts, thereby facilitating the operation of building the heel blanks and minimizing the danger to the operator. In carrying out this part of the invention, we employ a pivoted heel-blank holder, which normally occupies an inclined position, its upper end extending outward, or toward the operator, and being provided with a gage-plate against which the heel lifts are alined, and which holder, by means of a treadle, may be brought to a vertical position for the purpose of having the lifts nailed together and the heel blank pressed down into the holder by parts automatically operated by the machine and placed in operation by the movement of the heel blank holder.

A further important feature of the invention is the provision of novel means for automatically compressing and nailing the compiled lifts, and pressing the heel blank thus formed into the heel blank holder.

A still further important feature of the invention is the provision of a rotatable container for supplying lifts of the desired size and in the required order to the operator. Preferably, two of such containers

are employed, located on either side of the operator.

The invention is also concerned with various details of construction and combination and operation of parts whereby the general object of the invention as above outlined is attained.

The invention is illustrated in the accompanying drawings, in which:

Fig. 1 is a front view of the machine partly in elevation and partly in section.

Fig. 2 is a sectional view on the line 2—2 of Fig. 1.

Fig. 3 is an enlarged front elevation of the upper part of the machine shown in Fig. 1.

Fig. 4 is an enlarged side elevation, partly in section, of the upper part of the mechanism shown in Fig. 3.

Fig. 5 is a section on the line 5—5 of Fig. 4.

Fig. 6 is a sectional view illustrating in plan the guard surrounding the heel former.

Fig. 7 is a perspective view of one of the heel forming plates.

Fig. 8 is an enlarged side elevation, partly in section, of the upper portion of the machine shown in Fig. 2.

Fig. 9 is a section on the line 9—9 of Fig. 8.

Fig. 10 is an enlarged side elevation illustrating the heel blank holder.

Fig. 11 is a central vertical section on the line 11—11 of Fig. 12.

Fig. 12 is a view in front elevation of the upper part of the heel blank holder.

Fig. 13 is a horizontal sectional view on the line 13—13 of Fig. 10, the heel blank holder being assumed to be in the vertical position shown by dotted lines.

Fig. 14 is a substantially horizontal sectional view on the line 14 of Fig. 10.

Fig. 15 is a fragmental enlarged view showing a portion of one of the lift containers and the mechanism immediately associated therewith.

Fig. 16 is a perspective view of a spring; and

Fig. 17 is a view in front elevation of the part shown in Fig. 15, and on the same scale.

The numeral 1 indicates the base of the machine on which is supported the main frame 2, the lower end of which rests upon and is secured to cross-beams 3 secured at

their ends to the side members of base 1. The numeral 4, Figs. 1, 2, and 10, indicates a heel-blank holder which is pivotally mounted at 5 in and between brackets 6, provided at the lower end of frame 2 at the front side thereof. The holder 4 comprises a back plate 7, Fig. 14, and a front or breast plate 8, the back plate being preferably in the form of an angle-iron, so as to present a V-shaped recess for receiving the rounded portion of the heel-blank, and the breast plate 8 being flat so that the breasts of the heel-blanks may aline against it. Secured to either side of the breast-plate 8 and centrally thereof is a plate 9, which plates are connected by an integral yoke 9^a, having an arm 10 projecting rearward therefrom. To the rear end of the arm 10 is connected one end of a coil spring 11, the upper end of which is secured to the frame of the machine. Secured to the back-plate 7 is a plate 12 having on either side lugs 13 which rest upon the upper side of the yoke 9^a. The numeral 14 indicates a metal strap which embraces the breast plate 8 and is secured at its free end to the back plate 7. Mounted in this strap is a turn screw 15, the end of which bears against the front of the breast-plate 8. By means of the screw 15, the back-plate 7 may be adjusted toward or from the breast-plate 8 to cause the holder to have the proper size for the heel-blank being formed. Mounted at the upper end of the breast-plate 8 is a gage-plate 16, Fig. 11, having a projection 17 at its upper end on its rear side. The plate 16 is provided with a longitudinal slot 18 through which passes a screw 19 having its head counter-sunk in the breast plate 8. A guard 20 is applied to the front side of the plate 16, and a nut 21 on the screw 19 holds the guard in place and clamps the plate 16 in the proper adjusted position. In other words, by the means described, the plate 16 may be raised or lowered according to the height of the heel-blank being built; the adjustment being such that when the last lift is applied its breast edge will engage under the projection 17 as clearly shown in Fig. 10. Mounted on the front side of the breast plate 8 is a spring arm 22 which has a projection 23 at its upper end extending inward over the upper end of the breast plate 8, and provided with an inclined surface at 23^a. Screw 19 passes through the lower end of the arm 22 and a washer 24 is inserted between said arm and the guide plate 16. When the nut 21 is tightened the arm 22 will be clamped in position. In proceeding according to my invention, and as shown by Fig. 10, as each heel-blank is compressed it is forced downward into the holder 4, that is to say, between the back-plate 7 and the breast-plate 8, and in this movement the breast edge of the heel will force back the arm 22 by engaging the upper

inclined side of the projection 23; and the movement is so regulated that at its termination the top lift passes the projection 23 and the latter will spring out and engage over the breast portion of the top lift, and thereby prevent the heel-blank from being forced upwardly by expansion of its lifts, or of the lifts of preceding heel-blanks placed under compression, so that the space for building the heel blanks is always maintained uniform, and all of the heel blanks are held under compression. This latter result is largely secured, however, by frictional engagement of the heel-blanks with the walls of the holder. 80

In order to shape the heel-blank before it is compressed and nailed, we provide a heel-former and locate the same in the line of movement of the upper end of the holder 4 containing the assembled lifts. Referring particularly to Figs. 3 and 4, the numeral 25 indicates a plunger, on the lower end of which is secured the heel-former, indicated generally by the numeral 26. This heel-former comprises a cap-plate 27 which is secured on the end of the plunger 25 by means of a binding screw 28. Extending downward from either side at the rear of the cap plate 27 are three arms, those at the sides being indicated by the numeral 29 and the arm at the rear by the numeral 30. Each of these arms is provided with a central longitudinal slot in which a series of plates are placed in superimposed relation, and adjusted to conform to the outline of the heel-blank at the rear and sides, respectively, after which they are secured in position by means of binding screws 31, having screw-threaded engagement in the lower end of arms 29 and 30 and engaging the lower plate in each arm. The plates in the side arms 29 are indicated by the numeral 32 and those in the rear arm 30 by the numeral 33. When the heel-blank has been built on the upper end of the holder 4, the latter is thrown inward, forcing the lifts between the two sets of plates 32 at the side of the heel former 26 and against the plates 33 at the rear thereof, thereby forming or shaping the heel blank. Mounted on the front 110 of the heel-blank holder 4 are sheet metal guards 34 which serve to protect the clothing of the operator from contact with the paste which accumulates on the outside of the holder. The holder 4 is moved inward 115 beneath the plunger 25 by means of a treadle 35, Figs. 2 and 10, which is secured substantially centrally on a rod 36 which is pivotally mounted at its ends in bearings 37 secured on the side members of the base 1. The treadle 35 is in the form of a bell-crank lever, having an upwardly extending arm 38 which is pivotally connected to the outer end of a pull-rod 39, the other end of said pull rod having a pin 40 which works 120

in a slot 41 in a slide-rod 42; the outer end of this rod is pivotally connected at 43 to the holder 4 below the point 5 of pivotal connection therewith with the frame. The 5 pin 40 also connects the inner end of the pull rod 39 with one arm 44 of a bell-crank lever 44^a, the other arm 45 of which has the lower end of a coil spring 46 secured to its inner end. The said bell-crank lever is 10 pivotally connected at 47 in opposite sides of a hollow, semi-cylindrical member 48 provided at the lower end of the main frame 2. The arm 10, heretofore referred to (see Figs. 2 and 10), extends into the casting, 48, 15 and the spring 11 connected to said arm passes through an opening in the upper side of the casting 48. By pressing down on the treadle 35 it will be seen that the rod 32 will cause the lower end of the holder 20 4 to be thrown outward and the upper end of said holder inward. The upper end of the coil spring 46 (see Fig. 2) is connected to a collar 49 which is secured on a vertically disposed rod 50. The lower end of this rod 25 passes through a bearing 51 provided in a bracket 52 secured to one of the frame members 3, and rests upon a bearing plate 53 which is secured on the end of the slide-rod 42. A spring 54 is interposed between the 30 bearing 51 and a collar 55 fixedly secured on the rod 50. The upper end of the rod 50 passes through an opening in a clip 56 and is provided with a rounded head 58. (See Fig. 8.) The numeral 59 indicates a 35 belt pulley which is loosely mounted on a drive-shaft 60, mounted in bearings 61 provided on the upper side of the frame 2. On the shaft 60 is a clutch-member 62 which is adapted to coöperate with a clutch-member 40 63 provided on the hub of the pulley 59. The clutch-member 62 is normally held out of engagement with the clutch-member 63 by engagement of the head 58 with an annular flange 64 provided on the outer end 45 of the clutch member 62. A coil spring 65 located in the wall of the bearing 61 operates to force the clutch member 62 into engagement with the clutch member 63 when the rod 50 is pulled downward to release engagement of the head 58 with the 50 annular flange 64. A cam member 66 is provided on the flange 64, which is adapted, by engagement with the side of the head 58 to release clutch-member 62 from engagement with the corresponding member 63. A coil spring 67 is secured at its lower end to a collar 68, fixedly secured on the rod 50, and at its upper end to the clip 56. This spring pulls the rod 50 upward and holds 55 it in the position shown in Figs. 2 and 8. The rod 50 is pulled downward to release the head 58 from engagement with the flange 64 by the action of the spring 46. As the treadle 35 is pressed downward the 60 holder 4 will first be thrown into the vertical position and immediately thereafter, the rear end of the rod 42 will pass from beneath the lower end of the rod 50. In this movement the outer end of the arm 45 will have been moved downward to extend the 65 spring 46, which, when so extended, has greater power than the spring 67; and hence when the plate 53 passes from under the end of the rod 50, said rod 50 will be pulled downward by the spring 46 against 70 the resistance of said spring 67, and the clutch-member 62 will be forced by the spring 65 into engagement with the clutch-member 63. On the forward end of the drive shaft 60 is mounted a cam disk 69 75 having a flat face 70, Figs. 1, 2, and 3. Secured on the disk 69 is a crank pin 71 having a cross-head 72, which is slidably mounted between transverse guides 73 secured by bolts 74 intermediate the ends of 80 a plunger 75, which is mounted for vertical movement in bearings 76 provided in a yoke-shaped portion 77 of the frame 2. The lower end of the plunger 75 carries a nailer 78 and is immediately over an abutment 79 (see 85 Figs. 4 and 8) secured to the forward side of the plunger 25 at the lower end thereof, said plunger 25, abutment 79, and heel-former 26 constituting a unitary member. Mounted in the abutment 79 is a nail holder 90 80 of any preferred construction, the plate 27 being provided with an aperture 81, through which nails may pass. The numeral 82 indicates a nail guide mounted on a plate 83 which is secured on the front of the lower 95 bearing 76 by a bolt 84. Assuming, now, that a nail, 85, is in the nail holder 79, that the holder 4 with the assembled heel blanks 86 thereon, has been moved to the vertical position, shown in Fig. 10 by dotted lines, 100 to bring the heel blanks within the heel former 26, and that the shaft 60 is rotating, the cross head 72 will cause the plunger 75 to descend so that the nailer 78 will enter the nail holder 80 and force the nail 85 105 110 therein into the heel-blank, and the lower end of the plunger 75 will strike the upper end of the abutment 79 and thereby force the plunger 25 downward, compressing the heel-blank and forcing it into the holder 4 115 and forcing preceding heel-blanks previously formed farther downward into the holder. Referring to Fig. 3, the numeral 87 indicates an arm which is secured intermediate its ends on the plunger 25, and is 120 provided on one end with a roller 88 which normally rests against the flat surface 70 of the disk 69. The other end of the lever is provided with a bearing 89 which is secured upon the upper end of a vertically disposed rod 90, the lower end of which is bent at right angles to provide an inward projection 91 which is secured in the lower end of the plunger 25. A coil spring 92 125 is secured at its upper end to a stud 93 on 130

the upper bearing 76 of the yoke member 77 and at its lower end to a collar 94 fixedly secured toward the lower end of the rod 90. The purpose of this construction is to permit the heel former 26 to be given a slight downward movement to compress the heel-blank before it is nailed. It will be seen that as the disk 69 is rotated by the shaft 60, the flat surface will pass off of the roller 88 and the circular portion of the disk will act as a cam which, engaging the roller 88, will force the arm 87, plunger 25, rod 90, and heel former 26 downward, then the nailer 78 will drive the nail 85 into the heel-blank, after which the lower end of the plunger 75 will strike the abutment 79 (Fig. 4) and complete the downward movement of the heel former 26, forcing the heel-blank into the holder 4. The numeral 95, Figs. 2, 3, 6, and 8, indicates a guard which is secured by means of a bolt 96 and jam nut 97 on the front of frame 2, and is provided at its front end with an upwardly turned lip 98. As the holder 4 is thrown inward the topmost lift will engage the under side of the lip 98 and be guided thereby to pass under the edge of the plate 27. Without this arrangement there would be danger of the top lift hitting the edge of said plate. The heel-blanks having been compressed, nailed, and forced into the holder 4, the continued rotation of the shaft 60 will raise the plunger 75 and cause the cam 66 (Fig. 8) to engage the head 58 and thereby withdraw the clutch member 62 from engagement with the clutch member 63. Further rotation of the shaft after the plunger 75 has been returned to its normal position, and the clutch members 62 and 63 disengaged, is prevented by means of a brake shoe 99 (Fig. 9) mounted on the upper side of the frame 2 to bear upon a friction disk 100 keyed on the shaft 60. A set screw 101 bearing upon the brake 99 regulates the degree of pressure of the brake upon the friction disk. There is no fly wheel on the shaft 60, and this brake mechanism prevents any tendency of the disk 69 to pass beyond the dead center position, shown in Fig. 3.

In order to enable the operator to select rapidly and readily the appropriate lifts to be used in building up the heel-blanks, the following mechanism is provided:

Referring particularly to Fig. 1, located on either side of the base 1 are brackets, 102, which afford bearings, 103, for two alining shafts 104, each of which is provided on its outer end with a bevel pinion 105 which is in mesh with a bevel gear 106, rotatably mounted on a stub shaft 107 secured in, and projecting upward from a side member of the base 1. Each of the gears 106 has a hub 106^a the bottom of which rests upon the top of a hub 107^a of the bracket 102, a set screw 108^a securing said hub 107^a in position on

the fixed stub shaft 107. Each of the shafts 104 is also provided on its inner end with a bevel gear 108, only one of these being shown (see Fig. 2). The bevel gear 108 is in mesh with a bevel pinion 109 which is secured on the end of a shaft 110 supported in a bearing 111 on the rear side of frame 2. The rear end of the shaft 110 has fixed thereon a pulley 112 and the rear end of the shaft 60 has fixed thereon a pulley 113. A belt 114 passes over the pulleys 112 and 113 for driving shaft 110. The numeral 115 indicates two lift containers; and as the construction and operation of both of these is the same, the following description will be based on one of said containers. The container 115 comprises a circular bottom 116, a central cylindrical member 117 projecting upward from the bottom, an outer circular casing 118 and a series of radial partitions 119 extending between the wall of the cylinder 117 and the casing 118 and which divide the container into a series of pockets 120. The lower end of the casing 118 terminates at some distance above the bottom 116 and is inclined inward as indicated by 121, thereby leaving an opening 122 between the bottom 116 and the lower end of the casing 118, through which lifts in the pockets 120 may be removed by the operator. In the center of the bottom 116 is a bearing 123, which receives the upper end of the shaft 107 and is adapted to rotate thereon. The container 115 as a whole, rests upon the top of the bevel-gear 106, a washer 124 being interposed between said gear and the bottom of the container. As the shaft 104 is rotated, the container 115 will be rotated by frictional engagement with the gear 106, if not prevented. Secured at intervals around the bottom of the container 115, and projecting slightly beyond the side thereof, are stops 125, Fig. 15, which are adapted to engage the edge of a lever 126, which is pivotally mounted at its inner end on a pindle 127 projecting upward from a bracket arm 128, which bracket arm is secured at one end to the front of the frame 2. The opposite end of this bracket arm is bolted to and supports a paste pot 129. Numeral 130 indicates a plate which covers a greater portion of this paste pot and provides, as well, a table. The free end of the lever 126 projects upward above plate 130, and the stops 125 are so positioned that when one of them is in engagement with lever 126 the container will be stopped with the center of one of the pockets 120 lying directly opposite the lever 126. A spring 131, shown in detail in Fig. 16, secured at one end on the inner side of the paste pot 129 tends normally to hold the lever 126 in the path of the stops 125. As the operator removes a lift from one or the other of the pockets 120 he can, in the same movement, engage 130

the lever 126 with his hand and pull it outward to release engagement with the stop 125, when the container 115 will again be placed in motion by the gear 106. The lever 126 is immediately moved inward by spring 131 to a position to be engaged by the next stop 125, which will cause the container to be stopped with the pocket containing the next size of lift required in position before 10 the operator. It will be understood that when the rotation of the container 115 is stopped, the top of the gear 106 simply slides over the washer 124. The numeral 132 indicates a paste-pad which normally 15 rests slightly above the top of the paste pot 129. The inner end of the table 130 terminates short of the outer edge of the paste-pad, leaving a space that affords access to the paste-pad by the operator. In order to 20 keep the pad 132 supplied with paste the following mechanism is provided:

Pivottally mounted in ears 133, Figs. 15 and 17, projecting from the rear end of the paste pot is an arm 134 which at its inner 25 end extends under the container 115 and is bent twice upon itself at right angles to provide a crank arm 135 on which is mounted a roll 136. The pad 132 is secured on one end of a lever-arm 138, the other end of which 30 is fixedly secured centrally to the arm 134, by a binding-screw 139. Secured on the under side of the container 115 is a circular rail 140 the bottom of which travels, when the container rotates, in contact with the roller 136, and serves to maintain the pad 35 132 in the elevated position shown in the full line in the views referred to. Said rail 140 is cut away at one point on inclined lines to provide a double, or substantially V-shaped cam-groove 141. The weight of the 40 pad is sufficient to overbalance the roller 136 and when, in the rotation of the container, the groove 141 passes over the roller 136, the same will rise, by passing up one 45 side of the groove, and thus allow the pad 132 to dip into the paste, and then the roller 136 will be forced downward by engagement therewith of the other side of the groove 141, and raise the pad, and the latter 50 will be held in its raised position by engagement of the rail 140 with roller 136 until the cam groove again passes over said roller.

It will be readily understood by those 55 skilled in the art that the pockets 120 are respectively supplied with lifts of the appropriate sizes, running in order, so that as each pocket in turn comes to rest opposite the operator, the said pocket will contain 60 lifts of the size desired. In some cases, the corresponding pockets of the container will contain the same size of lifts, where two lifts of the same size are to constitute a layer; and in others, the corresponding 65 pockets will contain lifts of different sizes,

so that with one hand the operator will take the larger lift and place it in position on the holder, or on a preceding lift, and with the other hand, take a smaller size lift and place it in position on the first lift selected. 70 As each lift is selected, the operator touches the lever 126 to permit the container to be rotated to bring a pocket containing the next size lift desired into position.

In a decked heel, the surface of the top of the heel extends at an incline to the breast instead of at right angles thereto, owing to the fact that the curved, or rear portion of the heel is built up higher than the breast portion. In order to compensate for this 75 difference in height between the front and rear of the heel blank and to cause the lifts to occupy a substantially horizontal position in the holder 4, wedge-shaped plates 80 142 are inserted between the heel blanks. 85 The manner of using these plates is to place a plate on the top of each heel-blank after it has been nailed and forced down into the holder, the next heel-blank being built up on the plate. One of the pockets 120 is 90 supplied with a number of the plates 142, and said pocket will be brought to position opposite the operator at the completion of a heel-blank by the revolution of the container 115. The cam-groove 141 is 95 preferably arranged approximately under the pocket 120 containing the plates 142 so that the paste pad 132 will be dipped into the paste and returned at the time when a spacing plate is to be used, which of course, 100 does not have to be supplied with paste.

It may be stated that, starting initially, that is, before any heel blanks are in the holder 4, a lift, or a heel-blank, or any other suitable form of support of the proper size to be frictionally engaged by the front and back plates of the heel-blank holder, is inserted in the top thereof, to support the first heel-blank built up. After that, each heel blank serves as a support for the next 105 heel blank being built. As the operation continues, a heel blank will be discharged from the lower end of the holder 4 as a heel-blank is pushed down into the upper end, and the length of the holder is such 110 that each heel-blank will be held therein under compression a sufficient length of time to permit the paste between the lifts to set before the heel-blank is discharged from the holder.

The embodiment of the invention illustrated in the drawings is susceptible of various modifications as to details of construction and operation without departing from the spirit of the invention.

We claim:

1. In a heel building machine, in combination with means for compressing and nailing a heel-blank, a movable holder for receiving a series of said heel-blanks in super-

imposed relation, and on which said heel-blanks are in turn built up, and means for moving said holder with a built-up heel-blank thereon beneath said compressing and 5 nailing means.

2. In a heel building machine, in combination with means for compressing and nailing a heel-blank, a movable holder for receiving a series of said heel-blanks in superimposed relation, and on which said heel-blanks are in turn built up, a heel-former located in the line of movement of said holder and the heel-blank built up thereon, and means for moving said holder to carry 10 the built up heel-blank thereon into said heel-former and beneath said compressing and nailing means.

3. In a heel building machine, in combination with means for compressing and nailing a heel-blank, a movable holder for receiving a series of said heel-blanks in superimposed relation, a heel-gage on the upper 20 end of said holder, against which said heel-blanks are in turn built up, and means for 25 moving said holder to bring the heel-blank thereon beneath said compressing and nailing means.

4. In a heel building machine, in combination with means for compressing and nailing a heel-blank, a movable holder for receiving a series of said heel-blanks in superimposed relation and on which said heel-blanks are in turn built up, means for moving said holder to bring the heel-blank 30 thereon beneath said compressing and nailing means, and means on the holder for retaining the heel-blank in position while it is being moved by said holder beneath said compressing and nailing means.

40 5. In a heel building machine, in combination with movable devices for compressing and nailing a heel-blank, a pivotally mounted holder for receiving a series of said heel-blanks in superimposed relation, and on which said heel-blanks are in turn built up, and means for tilting said holder to carry the built up heel-blank thereon beneath said compressing and nailing devices.

50 6. In a heel building machine, in combination with movable devices for compressing and nailing a heel-blank, a pivotally mounted holder for receiving a series of said heel-blanks in superimposed relation, and on which said heel-blanks are in turn built up, a heel-former located in the line of movement of said holder and the heel-blank built up thereon, means for tilting said holder to force the built up heel-blank 55 into said heel-former and beneath said compressing and nailing devices, and means for actuating the latter devices.

60 7. In a heel building machine, in combination with movable devices for compressing and nailing a heel-blank, a pivotally mounted holder for receiving a series of said

heel-blanks in superimposed relation, and on which said heel-blanks are in turn built up, a heel-former carried by said compressing device, and located in the line of movement of said holder and the built up heel-blank 70 thereon, means for tilting said holder to force the built up heel-blank thereon into said heel-former and beneath said compressing and nailing devices, and means for actuating the latter devices. 75

8. In a heel building machine, in combination with a movable device for compressing a heel-blank and a movable device for nailing a heel-blank, a movable holder for receiving a series of said heel-blanks in superimposed relation, and on which said heel-blanks are in turn built up, means for moving said holder with a built up heel-blank thereon beneath said compressing and nailing devices, and means for actuating 80 said nailing and compressing devices, the latter in advance of the former. 85

9. In a heel building machine, in combination with a movable device for compressing a heel-blank and a movable device for nailing a heel-blank, a movable holder for receiving a series of said heel-blanks in superimposed relation, and on which said heel-blanks are in turn built up, means for moving said holder with a built up heel-blank thereon beneath said compressing and nailing means, means for giving a preliminary compressing movement to said compressing device, and means for actuating 90 thereafter said nailing device and to simultaneously move the compressing device to the limit of its downward movement to force the heel-blank into said holder. 95

10. In a heel building machine, in combination with a movable device for compressing a heel-blank, and a movable device for nailing the heel-blank located above said compressing device, a movable holder for receiving a series of said heel-blanks in superimposed relation, and on which said heel-blanks are in turn built up, means for moving said holder with a built up heel-blank thereon beneath said compressing and nailing devices, a nail holder carried by said compressing device, means for imparting a preliminary movement to said compressing device, and means for thereafter actuating said nailing device to cause it to force the nail into said heel-blank and to engage said compressing device to move it downward 105 and thereby force the completed heel-blank 110 into said holder. 115

11. In a heel building machine, in combination with a holder for receiving a series of heel-blanks in superimposed relation, a heel-gage on said holder against which each heel-blank is in turn built up, means for forcing the completed heel-blank into said holder and means on said holder for engaging the last heel-blank forced into the holder. 125 130

to hold it in the position to which it has been forced in the holder.

12. In a heel building machine, a vertically-disposed plunger having a heel-former mounted on its lower end, a nail holder also mounted on the lower end of said plunger, a movable holder for receiving a series of heel-blanks in superimposed relation and on which said heel-blanks are in turn built up, means for moving said holder with a built up heel-blank thereon beneath said plunger, a vertically-disposed plunger carrying a nailing device located above said nail holder, a drive shaft, and means actuated by said drive shaft to move downward in order, first, the plunger carrying the heel-former and nail holder, then the plunger carrying the nailing device and then both plungers together.

20 13. In a heel building machine, in combination with means for compressing and nailing a heel-blank, a drive shaft for actuating said compressing and nailing means, a clutch for connecting said drive shaft with a source of power, a movable holder for receiving a series of heel-blanks in superimposed relation and on which said heel-blanks are in turn built up, means for moving said holder with a built up heel-blank thereon beneath said compressing and nailing means, clutch control means actuated in the movement of said holder for releasing said clutch, whereby the drive shaft may be actuated, and means for restoring the holder to its normal position after the movement described, said clutch-control means being released by the return of the holder to normal position and operating to disengage the clutch from the source of power.

40 14. In a heel building machine, in combination with means for compressing and nailing a heel-blank, a drive shaft for actuating said compressing and nailing means, a movable holder for receiving a series of heel-blanks in superimposed relation and on which said heel-blanks are in turn built up, means for moving said holder with a built up heel-blank thereon beneath said compressing and nailing means, means for restoring the holder to normal position after such movement, and means operating in connection with said holder for causing the drive shaft to be actuated in the first movement of the holder and for stopping the actuation of the drive shaft when the holder is restored to normal position.

60 15. In a heel building machine, a device on which a heel-blank may be built up, means for compressing and nailing the built up heel-blank, a rotatable member having a series of compartments adapted to

be provided with lifts of the varying sizes required by the operator, a continuous moving member for rotating said container by frictional contact therewith, and means under the control of the operator for stopping said container as each pocket is turned to position.

16. In a heel building machine, in combination with a device on which a heel blank may be built up, a rotatable container having compartments adapted to be provided with lifts of the varying sizes required by the operator, means controlled by the operator for intermittently rotating said container, a paste pot, a pad pivotally mounted in said paste pot and coöperating means carried by said container and pad, respectively, and operating to cause said pad to be dipped in the paste of said pot at certain stages in the revolution of said container.

17. In a heel building machine, in combination with a device on which heel-blanks may be built up, a rotatable container for lifts having a rail on its under side provided with a cam groove, a paste pot, and lever mechanism carrying at one extremity a pad located in said paste pot and at its other a roller normally engaged by said rail to hold said pad in an elevated position, whereby in the movement of said container said roller is adapted to enter the cam groove and permit the pad to dip into the paste in said pot, and in the continued movement of the container to pass out of said groove and thereby rock the lever mechanism and lift the pad out of the paste.

18. In a heel building machine, in combination with a device on which heel-blanks may be built up, a continuously rotating member, a container mounted on said member and rotatable by frictional contact therewith, said container having a series of compartments open at the periphery of the container for holding lifts of the varying sizes required by the operator, a circular series of stops on said container, and a pivoted, spring-controlled member normally resting in the path of said stops and adapted to be engaged in turn thereby to arrest the movement of the container as the respective compartments appear opposite the operator, said member having a portion for engagement by the hand of the operator to release its engagement with the respective stops.

In testimony whereof, we have hereunto set our hands.

JOHN E. MITCHELL.
